United States Patent Office

Des. 185,138
Patented May 12, 1959

185,138

SHIPPING CONTAINER

William Dickinson, Los Angeles County, Calif., assignor to Harvey Aluminum, Torrance, Calif., a corporation of California

Application February 24, 1958, Serial No. 49,786

Term of patent 14 years

(Cl. D58—12)

FIG. 2.

Fig. 1 is a perspective view of a shipping container taken from one side, one end and bottom thereof embodying my new design.

Fig. 2 is a perspective view thereof taken from the opposite side, opposite end and top thereof.

I claim:

The ornamental design for a shipping container, as shown.
